TOY

Harold D. Allen, East Hampton, Conn., assignor
to The Gong Bell Manufacturing Company,
East Hampton, Conn., a corporation of Con-
necticut

Application June 6, 1939, Serial No. 277,569

5 Claims. (Cl. 46—104)

My invention relates to improvements in toys and more particularly to a wagon type of toy which is drawn by a toy animal, figure or the like.

One of the objects of my invention is to provide a toy of novel construction which will simulate the natural movements of a fowl or the like, when the wheels of the toy revolve.

Another object of my invention is to provide a toy of the wagon drawn type in which leg members are movably mounted on the wheels of a figure located anterior to the wagon, and pedal members are secured to the lower end of said leg members, thus imparting to the figure the natural movements of a fowl or like, when the wheels revolve.

Another object of my invention is to provide a toy of the wagon type and drawn by a toy animal or figure, said wagon having a noise producing mechanism emitting noises corresponding to the natural noises or sounds produced by the animal imitated, when the wheels of the toy revolve.

Another object of my invention is to provide an improved toy of the wagon type and drawn by a toy figure or the like, which is sturdy in construction and effective in operation.

Other objects of my invention will be set forth in the following description and drawings, which illustrate preferred embodiments thereof, it being understood that the above statement of the objects of my invention is intended generally to explain the same without limiting it in any manner.

Fig. 1 is a side view of my improved toy.

Fig. 2 is a top plan view thereof.

Fig. 3 is a sectional view on line 3—3 of Fig. 2.

Fig. 4 is a bottom plan view.

Fig. 5 is a front view showing only the front portion of the toy.

Fig. 6 is a diagrammatic view, showing the legs of the toy in various positions.

Fig. 7 shows another construction for animating the leg members of my toy device.

Referring to the drawings, my toy device generally comprises an animated fowl figure F and a wagon or cart W, said figure being rigidly joined to said cart by a harness H.

Referring to the animated figure F, said figure comprises a body member 5, made of wood or any other suitable material. Said body member 5 may be cut out and painted to simulate any animal or figure, such as a hen, for example, as illustrated in the drawings.

Body member 5 is mounted on wheels 1 and 2 by means of axle 6 passing through the centers of said wheels and through the lower part of

body member 5, said wheels being rigidly connected to said axle.

As shown in Fig. 5, wheels 1 and 2 have movably mounted thereon leg members 7 and 8 respectively, said leg members being generally of stepped shape and being identical in construction and contour. Pedal members 9 and 10 are secured to the lower ends of leg members 7 and 8, said pedal members being made preferably of a soft pliable material so that a flapping motion 10 will be produced when leg members 7 and 8 are animated.

As clearly shown in Figs. 1 and 3, leg members 7 and 8 are formed with upper vertical slots 12 and 13, and lower vertical slots 14 and 15, respectively. Between the vertical arms of leg members 7 and 8, horizontal shoulders 16 and 17 are formed, said shoulders being at least as wide as the thickness of either of wheels 1 or 2, so as to permit free rotation of said wheels between 20 the lower vertical arm of said leg members and body member 5, as shown in Fig. 5. The bottom portion of the lower vertical leg arms are horizontally bent to form horizontal base members 19 and 20. The outer free end of said base members are turned inwardly to secure pedal members 9 and 10 to said base members.

Pins 21 and 22, mounted diametrically opposite on the outer faces of wheels 1 and 2 respectively, are slidable relative to lower vertical slots 14 and 15, respectively. The upper slots 12 and 13 are slidable on the inwardly bent end portions 22 and 24 of harness H.

Leg members 7 and 8 are animated as follows:

The toy is pulled by a string S or the like and 35 wheels 1 and 2 are thus caused to be revolved.

Referring to Fig. 6, A, B, C and D represent different positions of one of the leg members. Starting from position A, the leg member is at its lowest position and as the wheel rotates ninety 40 degrees, the leg member moves backwards and upwardly, taking the position designated as position B. When the wheel has completed a full half revolution, the leg member reaches its highest position and lies directly above the axle of 45 the wheel. As the wheel rotates for another ninety degrees, the leg member moves forwardly and downwardly to assume position D and as said wheel completes a revolution, the leg member returns to its original relative position A. 50 Leg members 7 and 8 assume opposite positions since pin members 21 and 22 are diametrically opposed. That is, when leg member 7 assumes position B, leg member 8 will assume position D and vice versa. When leg member 7 assumes po- 55

sition A, leg member 8 will assume position C and vice versa. It should be noted that the distance between the lower end of the upper slot and the upper end of the lower slot is equal to or less than the distance between the bent in end of harness H and the eccentric pin, when said pin is at its highest position. The distance between the upper end of the upper slot and the lower end of the lower slot is equal to or greater than the distance between the bent in end of harness H and the eccentric pin, when said pin is at its lowest position.

As will be noted from the drawings, harness H consists of two bent wires, 25 and 26, whose front parts run parallel, abut and are secured to each side of body member 5 by means of staples 27. The extreme front end of each wire is bent outwardly and then inwardly so as to allow leg members 7 and 8 to freely slide between the harness and the body member (see Fig. 2). The rear part of harness H flares outwardly and is secured to the underside of the front part of wagon W by means of cross-bar 28, bolt 29 and nut 30.

25 Wagon W is mounted on a pair of wheels 31 and 32, said wheels rotating with shaft 33, said shaft being rotatably connected to a pair of blocks 34 and 35 by means of staples 36. Said blocks 34 and 35 are also secured to the underside 30 of the wagon by staples 36.

35 Fig. 3 shows a noise producing mechanism in association with wagon W. Said noise producing mechanism comprises a disc member 37 rigidly connected to shaft 33 so as to rotate therewith. Said disc member 37 has an irregular peripheral edge having its extreme portion 38 serrated.

An aperture 39 is formed in base 40 of wagon W. A resonant diaphragm member 41, having a continuous side wall 42 coinciding with the inner face of aperture 39, is held in aperture 39 by means of staples 43. The upper end of aperture 39 is covered by lid 44, said lid having a hole 45 formed therein. Rigidly connected to the lower face of diaphragm 41 is the resilient member 46. As wheels 31 and 32 rotate, disc 37 is caused to rotate and when the free end of resilient member 46 contacts serrated portion 38 of disc 37 diaphragm 41 is caused to vibrate thus producing a noise or a series of sounds, and when the non-serrated portion 47 of disc 37 contacts the free end of resilient member 46, diaphragm 41 does not vibrate and no noise or sound is produced. The relative duration of the noise emitted depends upon the length of serrated portion 38. Thus by varying the shape of disc 37 and by varying the shape, size and resonance of diaphragm 41, different types of sounds may be produced to simulate the natural sounds of the figure drawing the wagon. In the present case, disc 37 is so shaped and diaphragm 41 so formed that the noises or sounds emitted simulate a cackling hen.

I have shown the leg members animated by two wheels having diametrically opposed eccentric pins mounted thereon but it is quite obvious that a single wheel may replace the two wheels as shown in Fig. 7. More particularly, a wheel 50 is rigidly mounted on crank 51. The central shaft 52 of crank 51 is rotatable in bearings 53, said bearings being rigidly connected to the lower part of the body member 54. Said crank 51 is formed with the diametrically opposed handle portions 55, said handle portions having the enlarged heads 56. A pair of pins 57 are located in body portion 54 vertically above the shaft 52 of crank 51. The leg members 58, having a pair

of vertical slots formed therein, are connected and operate in the same manner as the leg members of the embodiment already described and differ therefrom only in shape.

I have shown and described preferred embodiments of my invention and it is obvious that numerous changes and omissions may be made without departing from its spirit. Likewise, I do not wish to be limited to any specific form or type of animal or figure nor to any particular type of wagon or cart. Likewise, the noise making mechanism may be incorporated in the figure instead of in the wagon as described.

I claim:

1. An animated figure of the character described comprising a body member simulating an animal or the like, wheels upon which said body member is mounted, an eccentric pin mounted on each of said wheels, leg members having upper and lower openings formed therein, each of said leg members being movably mounted upon each of said wheels, the lower openings being slidably engaged by the eccentric pins, the upper openings being also slidably engaged by means mounted on the body member, and a pedal member secured to the base of each leg member.

2. An animated toy of the character described comprising a wagon and a figure positioned anterior to and rigidly connected to said wagon, wheels upon which said wagon and figure are mounted, an eccentric pin mounted on each of the wheels of said figure, step-shaped leg members having upper and lower slots formed therein, each of said leg members being movably mounted upon each of the wheels of said figure, the lower slot of each leg member being slidably engaged by each eccentric pin, the upper slot of each leg member being slidably engaged by a stationary pin mounted on the body of the figure, and a pedal member secured to the base of each leg member.

3. An animated toy of the character described, comprising a wagon and a figure positioned anterior to said wagon, a harness connecting said figure to said wagon, one end of said harness being connected to the body of the figure, the opposite end of said harness being connected to the wagon, wheels upon which said wagon and figure are mounted, an eccentric pin mounted on each of the wheels of said figure, stepped shaped leg members having upper and lower slots formed therein, each of said leg members being movably mounted upon each of the wheels of the figure, the lower slot of each leg member being slidably engaged by each eccentric pin, the upper slot of each leg member being slidably engaged by the end portion of the harness connected to each face of the body of the figure, and a pedal member secured to the base of each leg member.

4. A toy of the character described comprising an animated figure simulating an animal or the like mounted on a pair of wheels, said wheels being rigidly joined by a shaft passing through the bottom of said figure, a pin eccentrically mounted on each wheel, said pins being diametrically opposed, a pair of step-shaped leg members having upper and lower slots formed therein, the lower slots of said leg members being slidably engaged by said eccentric pins, the upper slots of said leg members being engaged by the inwardly bent termini of a harness which joins said animated figure to a cart, the upper arms of said leg members abutting the figure and joined to the lower arms of said leg members by outwardly extending horizontal shoulders, the

lower arms of said leg members abutting the wheels, the bases of said leg members being bent horizontally outward and having pedal members secured to said bases, a cart in combination with said figure secured to the opposite end of the harness, said cart being mounted on a pair of wheels, said wheels being rigidly joined by a shaft member.

5. A toy of the character described comprising a figure simulating an animal or the like mounted on a pair of wheels, an eccentric pin positioned on each of said wheels, step-shaped

leg members having upper and lower slots formed therein, each of said leg members being movably mounted upon each of the wheels, the lower slot of each leg member being slidably engaged by each eccentric pin, the upper slot of each leg member being slidably engaged by fixed means mounted in the body of the figure, the bases of each of said leg members being bent horizontally outward and having a pedal member secured thereto.
